UNITED STATES PATENT OFFICE.

HERBERT S. KIRK, OF NEW CASTLE, PENNSYLVANIA.

DESIGN FOR A SOUND-REPRODUCER HORN.

Application filed February 24, 1925. Serial No. 12,458. Term of patent 14 years.

To all whom it may concern:

Be it known that I, HERBERT S. KIRK, a citizen of the United States of America, residing at New Castle, in the county of Lawrence and State of Pennsylvania, have invented a new, original, and ornamental Design for Sound-Reproducer Horns, of which the following is a specification, reference being had to the accompanying drawing, forming part thereof.

Figure 1 is a perspective view of a sound reproducer horn showing my new design;

Figure 2 is a top plan view.

Figures 3 and 4 are respectively rear and front elevational views.

Figure 5 is a perspective view looking directly at the side and at a slight angle downwardly.

I claim:

The ornamental design for a sound reproducer horn, as shown.

HERBERT S. KIRK.
